UNITED STATES PATENT OFFICE

ALICE MORIN STOPFORD, OF NEW YORK, N. Y.

MEDICAMENT APPLICATOR FOR FEET

Application filed April 3, 1929. Serial No. 352,214.

This invention relates to new and useful improvements in medicament applicators and has particular reference to a novel, simple, and efficient means whereby a suitable medicament may be maintained in engagement with calloused portions of the feet to remove the same from the feet.

Usually calloused portions grow on the ball of the foot and my novel applicator provides means whereby a drawing or removing substance may be maintained directly in contact therewith while the particular individual is sleeping.

Generally my novel applicator consists of a medicament holding cup the edge of which at the open end thereof is shaped to conform to the curvature of the ball of the foot around the edge of the calloused portion, means being provided for tightly maintaining the cup in engagement over the calloused portion and to prevent the material within the cup from flowing therefrom.

In the drawing:

Figure 1 is a side elevation of a human foot with the ball of which is associated my improved medicament applicator.

Figure 2 is a detailed transverse section through the cup element.

Figure 3 is a top plan view and,

Figure 4 is a side elevation of the means for maintaining the cup in engagement with the foot.

Now having particular reference to the drawings my novel applicator consists of a cup 5 preferably of glass, but of any suitable material. The edge of the cup at its open side is of sufficient diameter as to enable the cup to be arranged entirely over the calloused portion of the ball of the foot A and as is illustrated in Figure 3 the cup is of general oval shape at its open edge and is of somewhat greater length than width. The rear edge of the cup is flared outwardly to provide a lip 6 for close engagement with the ball of the foot at the rear edge of the calloused portion and the forward edge 7 of said cup is of a slightly lesser flare than the rear edge and is shaped to conform to the shape of the foot between the inner ends of the toes and the forward edge of said cup.

Also the said upper edge at opposite ends of the cup are so formed as to tightly engage the ball of the foot at opposite ends of the calloused portion. As a matter of fact this upper edge of said cup is of a shape to conform to the contour of the ball of the foot around the marginal edge of the calloused portion thereof, so as to provide a fluid tight joint between the cup and the foot when the cup is engaged with the foot and is practically filled with a medicament in the form of a liquid or semi-liquid or solid.

In order to maintain the cup in relatively tight engagement with the ball of the foot to prevent the substance therein from spilling therefrom there is provided a pouch of a suitable fabric and designed for engagement entirely over the cup 5 as illustrated in Figure 1. The ends of the pouch are formed to provide tabs 9 from which are extended lengths of suitable fabric 10-10 provided for engagement around the ankle of the leg directly above the heel and to be tied thereto as fully illustrated in Figure 1.

In view of the foregoing description when considered in conjunction with the accompanying drawing it will be apparent I have provided efficient means whereby a medicament may be maintained in engagement with a calloused portion upon the ball of the foot and even though I have herein shown and described the applicator as consisting of certain detailed structural features, it is nevertheless to be understood that some changes may be made therein without affecting the spirit and scope of the appended claim.

Having thus described my invention what I claim as new and desire to secure by Letters-Patent, is:

In a medicament applicator for foot callouses, a medicament receiving cup for application at its open side to the foot surrounding the callous, a pouch for engagement entirely over the cup, said pouch being of a shape conforming substantially to the outer surface of the cup and means associated with the opposite ends of the pouch whereby it may be tightly secured to the foot.

In testimony whereof I affix my signature.

ALICE MORIN STOPFORD.
